[57] **CLAIM**

The ornamental design for a splatter shield, as shown and described.

DESCRIPTION

FIG. 1 is a side, top perspective view of the splatter shield with the handle and three spring clips shown in phantom;
FIG. 2 is a top view thereof;
FIG. 3 is a bottom view thereof;
FIG. 4 is a right side view thereof;
FIG. 5 is a left side view thereof;
FIG. 6 is a front view thereof; and,
FIG. 7 is a rear view thereof.

The features shown in phantom do not form part of the claimed design.
